UNITED STATES PATENT OFFICE.

JEREMIAH ERWIN, OF CHICAGO, ILLINOIS.

BOTTLE-CAP FLUID DISPENSER AND SPREADER.

1,378,016.

Specification of Letters Patent. Patented May 17, 1921.

Application filed December 22, 1919. Serial No. 346,519.

To all whom it may concern:

Be it known that I, JEREMIAH ERWIN, a citizen of the United States, and a resident of the city of Chicago, in the county of Cook and State of Illinois, have invented certain new and useful Improvements in a Bottle-Cap Fluid Dispenser and Spreader; and I do hereby declare that the following is a full, clear, and exact description of the same, reference being had to the accompanying drawings, and to the numerals of reference marked thereon, which form a part of this specification.

This invention relates more particularly to a bottle cap fluid dispenser and spreader in which the bottle cap is adapted to provide the spreading surface and in which the fluid is dispensed from the bottle through an aperture in the cap which is closed by spring controlled means.

In bottle caps of this type as heretofore constructed the springs controlling the closing of the aperture were quite complicated and of such construction that they were soon deteriorated by the action of the fluid in the bottle and failed to effectually close the aperture.

It is therefore an object of this invention to provide a bottle cap having an aperture therein which is closed by spring controlled means.

It is a further object of this invention to provide a cover for a fluid container having a spring controlled aperture therein and having a portion of the cover adapted to be used for spreading the fluid.

It is an important object of this invention to provide an apertured cover for a container having means for closing the aperture, said means being operated by a single wire leaf spring secured within the cover.

Other and further important objects of this invention will be apparent from the disclosures in the drawings and specification.

The invention (in a preferred form) is illustrated in the drawings and hereinafter more fully described.

On the drawings:

Figure 1 is a front elevation of a bottle having a cap embodying the principles of this invention.

Fig. 2 is a fragmentary rear elevation of a bottle having a cap embodying the principles of this invention.

Fig. 3 is a section on line 3—3 of Fig. 1.

Fig. 4 is an elevation of the ball and

spring aperture closing means embodying this invention.

Fig. 5 is a fragmentary elevation of a bottle having a modified form of cap embodying the principles of this invention.

Fig. 6 is a section on line 6—6 of Fig. 3.

Fig. 7 is a detail showing a method of attaching the aperture closing ball to the leaf spring.

As shown on the drawings:

The reference numeral 1 indicates a container having an external flange 2 at the top thereof. A cap 3, having an aperture 4 and a flat surfaced portion 5, is secured to the flange 2 by a clamping ring 6, and an airtight joint is assured by the use of a packing 7 between the clamping ring 6 and the flange 2. The aperture 4 is closed by means of a ball 8, which is releasably held in position in the aperture by a wire leaf spring 9, which is secured inside the cap 3 and opposite the aperture by brazing or other suitable means. The leaf spring 9 consists of a straight spring wire bent upwardly to form a bight 10, which serves to force the ball 8 into the aperture 4. The side of the bight 10, which is opposite the aperture 4, is bent to conform to the casing 3, with which it is in contact. Internal projections 11 on the cap 3 serve to prevent the spring 9 from being displaced laterally. It will be seen from the above construction that the spring 9 and the ball 8 are secured only to the cap 3, a feature which makes possible the removal of the cap 3 without displacement of or injury to the spring or ball.

The operation is as follows:

When the top of the bottle 1 is tilted downwardly the fluid contained therein will flow into the cap 3. To dispense the fluid (as glue, mucilage, etc.) from the bottle the ball 8 is pressed against the surface on which it is desired to place the fluid. This pressure on the ball 8 causes it to recede into the cap 3, thus opening the aperture 4 and permitting the fluid to escape. The flat surface 5 may then be used to spread the fluid evenly over the surface on which it is poured. As soon as the pressure is removed from the ball 8 the action of the leaf spring 9 forces the ball back into the aperture thus sealing the bottle. Due to the shape and peculiar arrangement of the leaf spring 9, the fluid does not adhere to it and interfere with its action.

I am aware that numerous details of con-

struction may be varied through a wide range without departing from the principles of this invention, and I therefore do not purpose limiting the patent granted otherwise than necessitated by the prior art.

I claim as my invention:

1. In combination, a bottle, a dome-shaped cap closing said bottle, a portion of said cap being flattened to provide a plane surface oblique to the axis of said bottle and at one side thereof, an aperture in the curved surface of said cap, a valve for closing said aperture, a spring for holding said valve in closing position, said spring having a portion attached to the inner wall of the cap, a portion attached to the valve and at an angle to the first named portion and a portion connecting the said two portions and forming a compound curve, all the portions of said spring being in one plane, the flattened portion of said cap being on the side of said aperture opposite the bottle.
2. In combination, a bottle, a dome-shaped cap closing said bottle, a portion of

said cap being flattened to provide a plane surface oblique to the axis of said bottle and at one side thereof, an aperture in the curved surface of said cap, a valve for closing said aperture, a spring for holding said valve in closing position, said spring having a portion attached to the inner wall of the cap, a portion attached to the valve and at an angle to the first named portion and a portion connecting the said two portions and forming a compound curve, all the portions of said spring being in one plane, the flattened portion of said cap being on the side of said aperture opposite the bottle, and indentations in the cap at each side of said spring to assist in securing the spring in place.

In testimony whereof I have hereunto subscribed my name in the presence of two subscribing witnesses.

JEREMIAH ERWIN.
